UNITED STATES PATENT OFFICE

94,454

DESIGN FOR A TOY PENGUIN

Cecilia Brockhaus Steele, Kansas City, Mo.

Application November 8, 1934, Serial No. 53,941

Term of patent 7 years

To all whom it may concern:

Be it known that I, Cecilia Brockhaus Steele, a citizen of the United States, residing at Kansas City, Jackson County, Missouri, have invented a new, original, and ornamental Design for a Toy Penguin, of which the following is a specification, reference being had to the accompanying drawing, forming part thereof.

In the drawing:

Fig. 1 is a perspective view, and

Fig. 2 is a front elevational view of a toy penguin, showing my new design.

I claim:

The ornamental design for a toy penguin, as shown.

CECILIA BROCKHAUS STEELE.
